UNITED STATES PATENT OFFICE.

WILLIAM C. McCULLOUGH, OF BUCYRUS, OHIO.

PNEUMATIC CUSHION.

No. 871,811.

Specification of Letters Patent.

Patented Nov. 26, 1907.

Application filed July 13, 1906, Serial No. 326,129.

To all whom it may concern:

Be it known that I, WILLIAM C. McCULLOUGH, a citizen of the United States, residing at Bucyrus, in the county of Crawford and State of Ohio, have invented certain new and useful Improvements in Pneumatic Cushions; and I do declare the following to be a full, clear, and exact description of the invention, such as will enable others skilled 10 in the art to which it appertains to make and use the same:

This invention relates to improvements in pneumatic cushions for elastically distancing two structures, and more particularly for 15 use between the axles and the bodies of vehicles for absorbing shocks, jars and jolts.

The object of the invention is to provide a shock absorbing device of this character, which will be simple, durable and comparatively inexpensive in construction and very 20 effective for the purpose intended, so that its use upon the vehicle will dispense with the necessity of pneumatic tires upon the same.

With the above and other objects in view, 25 my invention consists in the novel construction, combination and arrangement of devices hereinafter described and claimed.

In the accompanying drawings,—Figure 1 is a view showing the application of my invention; Fig. 2 is an end elevation of the cushioning device; Fig. 3 is a longitudinal sectional view through the same; and Fig. 4 is a transverse sectional view.

Referring to the drawings by numeral, 1 35 denotes my improved pneumatic cushion or shock absorber, which as shown in Fig. 1 is mounted between an axle 2 and a body-supporting spring 3 of a vehicle of any description, but which may be interposed between 40 any two structures which it is desired to elastically distance.

The device 1 consists of upper and lower cup-shaped members or holders 4, 5, and an interposed, inflated, hollow body 6 of elastic 45 material, such as rubber. The cushioning body 6 is of oval form or egg-shaped, and is provided with a suitable valve connection 7, through which air may be introduced into said body by means of a pump or the like. 50 The members 4, 5, are similar in shape, each being of substantially semi-oval form and having upon its inner face a similar-shaped seat 8, which receives the body 6 and serves to retain the same therein. Each of said 55 members is formed upon its outer face with attaching flanges 9, which may be secured

upon the axle 2 and the spring 3 by bolts, clips or the like. The lower member 5 has formed at its opposite end upwardly-extending guide lugs 11, formed with vertically-arranged slots or openings 12, adapted to receive the reduced ends or projections 13 upon the upper member 4. The two members 4, 5, are slidably engaged with each other, the upper member 4 being 60 guided in its vertical movement by its ends 13 sliding in the slotted guides 11 on the member 5.

The construction, operation and advantages of the invention will be readily understood from the foregoing description, taken in connection with the accompanying drawings.

It will be seen that the device when interposed between the axle and the spring or body of a vehicle will entirely absorb the short, sudden jars or jolts, so that pneumatic tires may be dispensed with. By making the inflated body 6 and its holders or members 4, 5, of the form shown, it will be seen 80 that the body will be effectively retained between said members, and there will be little or no tendency of its working out.

Various changes in the form, proportion and the minor details of construction may be 85 resorted to without departing from the principle, or sacrificing any of the advantages of the invention, as defined by the appended claims.

Having thus described my invention, what 90 I claim as new, and desire to secure by Letters-Patent, is,—

In combination with a vehicle axle and a body-supporting spring, the herein described cushioning device comprising the pair of 95 holders, each having an integral projection on its outer side, at its center, formed with an attaching flange, one of said attaching flanges secured on the axle and the other secured to the center of the underside of the spring, one 100 of said holders having end guide lugs provided with guide openings, and the other having projections operating in said guide openings and a cushioning body between the said holders.

In testimony whereof I have hereunto set my hand in presence of two subscribing witnesses.

WILLIAM C. McCULLOUGH.
